Patented Sept. 16, 1975

236,812

BELL TIMER

James A. Draghi, Canton, Conn., assignor to
M. H. Rhodes, Inc., Avon, Conn.

Filed Apr. 12, 1974, Ser. No. 460,308

Term of patent 14 years

Int. Cl. D10—03

U.S. Cl. D10—40

FIG. 1.

FIG. 2.

FIG. 3.

FIG. 5.

FIG. 7.

FIG. 6.

FIG. 1 is a front elevational view of a bell timer showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a front elevational view of a modified form of the new design of FIG. 1 wherein all the surface ornamentation has been omitted.

I claim:

The ornamental design for a bell timer, substantially as shown and described.
